UNITED STATES PATENT OFFICE

ROY E. MATTOON, OF SUPERIOR, WISCONSIN

SHUTTER

Application filed April 26, 1928. Serial No. 272,989.

This invention relates to shutters and has special reference to a novel form of shutter for a radiator cover for automobiles, the principal object being to provide a more efficient and practical shutter than heretofore known.

Another object is to provide simple means whereby portions of the shutter may be opened while the remainder is closed, and the shutter is so designed that that portion opened initially is most desirable in the operation of the engine during cold weather to afford the necessary cooling with the minimum danger of freezing.

15 Other objects and advantages of the invention will appear in the further description thereof.

Referring now to the accompanying drawing, forming part of this application, and 20 wherein like reference characters indicate like parts:

Figure 1 is a front elevation of an automobile radiator as it would appear with one of the improved shutters applied thereto;

25 Figure 2 is a detailed fragmental view of the shutter operating mechanism partly in section and partly in elevation; and

Figure 3 is a fragmental view of the shutter operating mechanism.

30 1 represents the radiator front having a substantially rectangularly shaped opening therein, the closure for which comprised alternately disposed V-shaped members or vanes 2, they each being pivotally mounted at either end in any desired manner as for example by the gudgeons or pintles 3, one upon the uppermost end of each vane, terminating in the form of a crank arm 4, with the extreme end 5 of each extending within its respective slot 6 formed within the tubular roller 7. As is obvious this roller may be located transverse the upper end of the vanes or across the lower end thereof, whichever may be the more convenient, and journalled upon 45 the end gudgeons 8 in any desired manner.

Preferably adjacent one of these gudgeons 8 is formed as at 9 a circumferential groove for the reception of the operating rope or line 10, which may be wound thereabouts as 50 to prevent slipping, or in lieu thereof a

sprocket wheel and chain may be employed for the rotation of the shaft or roller 7. To one end of the operating line or rope 10 is attached a contractile helical spring 11 for normally holding the roller 7 against being rotated for the opened operation of the vanes, so that the latter normally remain in closed position, and the opposite end of the line 10 may lead to any convenient place within reach of the operator of the automobile so that by pulling same he may open the shutter to any extent desired; this being controlled as for example by a notched lever or operating rod indicated at 12 engageable with the fixed stop 13 on the dash board of the automobile.

To prevent rattling of the vanes of the shutter I install a spiral spring indicated at 14 within the tubular roller 7 and intermediate of the coils of which the termini 5 of the cranks 4 of the vanes are engaged and normally held against rattling by the spring.

It will be noted that the vanes 2 are as before stated V-shaped, every alternate one being inverted, and besides being novel and pleasing in appearance as compared with the horizontal shutters now in use, permit of those being widest at their upper ends being opened first so that in the initial operation of the automobile engine when cold the radiator will receive the cooling influence of the air entering same in the upper or hottest portion thereof while the intermediate vanes whose wider ends are at the bottom will remain closed thus keeping the cold air from the coldest part of the radiator until such time as it is desirable to admit the cooling influence of the air to the entire front of the radiator, when a continuance of the rotation of the roller 7 will cause the intermediate vanes to be opened. This action is brought about by the shape of the slots 6 which as clearly illustrated in Figure 3 of the drawings are formed obliquely in their leading termini for the vanes first to be opened and ending in a straight circumferential portion; whereas the shape of the slots for the vanes to be subsequently opened are just oppositely shaped, the termini 5 of the cranks of the latter extending within the circumferential portion of the slots during the ini-

tial operation of the roller and then subsequently being operated by the oblique portion thereof.

From the above it is apparent that I have devised an efficient form of shutter and operating mechanism therefor which may be regulated as desired from a closed to wholly opened position, and the construction of which may be varied somewhat from that of the embodiment here illustrated without departing from the spirit of the invention as defined in the following claims.

It is furthermore evident that the simple device for operating the vanes of the shutter may be employed with equal efficiency in the operation of horizontally disposed vanes.

Having thus described my invention, what I claim and desire to secure by Letters Patent, is:

- 20 1. A shutter of the class described comprising a plurality of alternate V-shaped and inverted V-shaped vanes.
- 25 2. A shutter of the class described comprising a plurality of alternate V-shaped and inverted V-shaped vanes and single means whereby alternate vanes may be simultaneously operated initially and the other alternate vanes subsequently operated.
- 30 3. A shutter of the class described comprising a plurality of vertically disposed alternate V-shaped and inverted V-shaped vanes and single means whereby alternate vanes may be simultaneously operated initially and the other alternate vanes subsequently operated.
- 35 4. A shutter of the class described comprising a plurality of vanes each having a larger area at one end than at the other and being alternately disposed.
- 40 5. In testimony whereof I affix my signature.
ROY E. MATTOON.
